UNITED STATES PATENT OFFICE.

THEODORE DOSSENBACH, OF ROCHESTER, NEW YORK.

PORTABLE BAND STAND.

Application filed September 24, 1921. Serial No. 502,905.

To all whom it may concern:

Be it known that I, THEODORE DOSSENBACH, a citizen of the United States, and resident of Rochester, in the county of Monroe and State of New York, have invented certain new and useful Improvements in Portable Band Stands, of which the following is a specification.

The present invention relates to portable band stands, and an object of the same is to provide a band stand which may be folded into compact form in order to permit it to be carried to and set up at any desired place. Another object of the invention is to provide a band stand having a top and a platform both made of sections, the sections being so connected that they may be folded together into compact form while, at the same time, providing a space which may receive band instruments, chairs and other paraphernalia for the band. Another object of the invention is to provide a portable band stand which may be readily folded into compact form and quickly separated to produce a platform having sections at different levels and a top acting as a sounding board and arranged above the platform.

To these and other ends, the invention consists of certain parts and combinations of parts all of which will be hereinafter described, the novel features being pointed out in the appended claims.

In the drawings:

Fig. 1 shows the vehicle in side elevation and in open position;

Fig. 2 shows the vehicle in side elevation and in closed position;

Fig. 3 shows the vehicle in rear elevation;

Fig. 4 is an enlarged section on the line 4-4, Fig. 1;

Fig. 5 is a similar section showing the adjacent parts in folded position;

Fig. 6 is a section on the line 6-6, Fig. 1;

Fig. 7 is a top view of a portion of the vehicle;

Fig. 8 is a section on the line 8-8, Fig. 1;

Fig. 9 one of the hinged connections between the hinged parts;

Fig. 10 is a detail view of one of the supporting braces; and

Fig. 11 is a fragmentary top view of the rear end of the vehicle.

Referring to the embodiment of the invention herein illustrated, 1 indicates the body of the vehicle which may be in the form of a self-propelled or motor vehicle.

This body is provided with two fixed main central platform sections 2 and 3, in this instance, arranged in different horizontal planes, the rearmost main central platform section being in a lower plane than the foremost section and both sections being arranged directly in rear of the seat 4 for the operator of the vehicle. The vehicle has a main central top section 5 arranged over platform sections 2 and 3 and supported at its forward end by a vertical wall 6 situated in rear of the seat 4 and at the forward edge of the platform section 3. The rear portion of the top 5 is supported, in this instance, by brace poles 7 which are mounted on the rear edge of the platform section 2. These brace poles have right and left hand threads 8 and 9 respectively arranged at their upper and lower ends and fitting respectively in sockets 10 and 11. The main central platform sections 2 and 3 extend farther outwardly at the side of the vehicle than does the top 5, and the top has a projecting edge 5^x.

At each side of the main central platform, main side platform sections 2^a and 3^a may be provided, these sections being hinged respectively to the main central platform sections 2 and 3 by hinges 12, which have removable pintles 13. Hinged to the main central top section 5 are main side top sections 5^a secured by hinges 12 with removable pintles, these hinges being so arranged that the ledge 5^x bridges the joints between the sections to keep out rain. As the main central platform sections 2 and 3 are wider than the main central top section 5, the main side top sections 5^a will fold downwardly, as indicated in Fig. 5, on the inner sides of the main side platform sections 2^a and 3^a. The main side sections 2^a and 3^a may have legs 14 hinged to the under side thereof at 15 and adapted to fold inwardly in parallel relation with the sections 2^a and 3^a when the sections 2^a and 3^a are folded vertically, as shown in Fig. 5. In order to support the main side top sections above the main side platform sections, brace poles 7 are employed which through right and left hand threads 8 and 9 detachably connect respectively with the sockets 10 and 11 on the top sections 5^a and the platform sections 2^a and 3^a respectively.

Arranged at the rear of the main central platform section 2 is an auxiliary central platform section 16. This auxiliary central

platform 16 is hinged at 17 to a ledge 18 which by brackets 19 is supported in a lower horizontal plane than the main central platform section 2. The main central top section 5 does not extend so far to the rear as does the ledge 18 and an auxiliary central top section 20 is hinged at 21 to the rear edge of the main central top section 5 under the ledge 5*, being supported at its rear or free edge by brace poles 7 which are connected to the auxiliary central top section 20 and the auxiliary central platform section 16 in the same manner as similar poles used in this invention. It is apparent that, when the auxiliary central top section 20 is swung downwardly, it will lie on the inner side of the auxiliary central platform section 16, when the latter is swung upwardly, as illustrated in Figs. 2 and 11. The auxiliary central platform section 16 may be supported in its lowered position by legs 22 which are pivoted at 23 to the under side of said auxiliary central platform section 16 and are foldable in parallel relation to said auxiliary platform section as illustrated in Fig. 2.

Auxiliary side platform sections 24 may be provided in rear of the main side platform sections 2* and these auxiliary side platform sections may be connected with the auxiliary central platform section 16 by hangers 25 which are secured to opposite sides of the auxiliary central platform section 16 to receive a timber or beam piece 26 on such auxiliary side platforms 24. Legs 27 pivoted at 28 to the auxiliary side platform sections 24 may serve to sustain the outer sides of the auxiliary side platform sections. This arrangement makes the auxiliary side platform sections detachable so that they may be removed in order to permit the folding of the main side platform sections 2* and the auxiliary central platform sections 16.

For covering the auxiliary side platform sections 24, two auxiliary side top sections 29 may be provided which through hinges 30 are connected to opposite sides of the auxiliary top section 20. These hinges permit the top sections 29 to fold on the upper side of the auxiliary top section 20 when the latter is swung downwardly, as illustrated in Figs. 2 and 11, one pair of hinges 30 being of greater length than the other so that their axis of turning is in spaced relation to the plane of the uppermost face of the top section 20, in order that the other top auxiliary section may fold first into parallel relation with the top section 20 to establish overlapping relation between the two auxiliary side top sections 29. Posts 7 detachably support the auxiliary top sections 29 above the auxiliary side platform sections 24, and have right and left hand threaded portions at opposite ends detach-

ably engaging in sockets 10 and 11. Hinges 12 with removable pintles 13 will connect the auxiliary side top sections 29 with the main side top sections 5*. Other details of construction which may be employed are cable rails 31 connecting the brace poles 7, as illustrated in Figs. 1 and 3. All of the top sections may be made hollow, as indicated at 32, the top wall being made of canvas, and the under wall 33 being in the form of a sounding board which will modify the sound in an advantageous manner. Receptacles or compartments 34 with hinged closures 35 may be arranged on opposite sides of the vehicle under the main platform sections 2 and 3 to receive the brace poles 7, cables 31 and other articles. Fastening devices 36 of any suitable type may be employed for securing the platform sections in elevated position.

From the foregoing it will be seen that there has been provided a portable band stand which may be moved to any desired position and opened up to provide a stand for a large number of band instrument players. The platform has sections at different levels or heights to obtain a band stand of conventional form, permitting the musicians to be positioned in the usual manner. A top is provided which modifies the sound so that a desirable effect is secured. The top and the platform are made of sections which are foldable into compact relation. When folded, a space is provided adapted to receive the platform sections 24, collapsible chairs and certain of the band instruments. The top sections are sustained against swinging upwardly by braces which interlock with the top sections and the platform sections, so as to tie the top and the platform together while permitting their disconnection in order to provide for the folding of the sections.

What I claim as my invention and desire to secure by Letters Patent is:

1. A portable stand comprising a central platform section, platform sections hinged to the central platform section, and a sectional top covering said platform sections, said top having all sections thereof lying in one plane and being hollow with its under side formed to act as a sounding board.

2. A portable stand comprising a platform formed of a plurality of sections, some of which lie in different horizontal planes from others, and a sectional top covering said platform and having all of its sections lying in one plane, said top being hollow and having its under side formed to act as a sounding board.

3. A portable band stand comprising a central platform section having two portions in different horizontal planes, side platform sections hinged on each side of the central platform section to swing up

- wardly, one side platform section being provided at each side of each of said two portions, a central top section, and side top sections adapted to lie in the plane of the 6 central top section and hinged to said central top section to swing downwardly.
4. A portable band stand comprising a main central platform section, main side platform sections hinged to the central 10 platform section, an auxiliary central platform section hinged at one end of the main central platform section to swing upwardly, auxiliary side platform sections arranged at opposite sides of the auxiliary central 15 platform section, a main central top section arranged over the main central platform section, main side top sections hinged to the main central top section to swing downwardly, an auxiliary central top section, and auxiliary side sections arranged 20 on opposite sides of the auxiliary central top section.
5. A portable band stand comprising a wheeled vehicle having a main central platform section provided with two portions in different horizontal planes, two main side platform sections hinged on each side of the central platform section to swing upwardly, the main side platform sections on 25 each side of the central platform section being in different planes and each hinged to one of the portions of the main central platform section to swing upwardly, an auxiliary platform section hinged to swing 30 upwardly at the rear end of the vehicle body, and auxiliary central platform sections secured on opposite sides of the said auxiliary central platform section.
6. A portable band stand comprising a 40 main central platform section, a main central top section, main side sections pivotally mounted on opposite sides of the main central platform section to swing upwardly, main side top sections pivotally mounted 45 on opposite sides of the main central top sections to swing downwardly, a central auxiliary platform section pivotally mounted in rear of the main central platform section to swing upwardly, an auxiliary central top section pivotally mounted in rear of the main central top section to swing 50 downwardly, auxiliary side sections mounted on opposite sides of the auxiliary central platform section, and auxiliary side top sections mounted on opposite sides of the auxiliary central top section.
7. A portable band stand comprising a 55 main central platform section, main side platform sections on opposite sides of the main central platform section, a main central top section, main side top sections on opposite sides of the main central top section, a ledge supported in a lower plane 60 than the main central platform section, an auxiliary central platform section hinged 65 to said ledge to swing upwardly, auxiliary side platform sections arranged on opposite sides of the auxiliary central platform section, an auxiliary central top section hinged at the rear of the main central top section 70 to swing downwardly, and auxiliary side top sections mounted on opposite sides of the auxiliary central top section.
8. A portable band stand comprising a main central platform section, main side 75 platform sections on opposite sides of the main central platform section, a main central top section, main side top sections on opposite sides of the main central top section, a ledge supported in a lower plane 80 than the main central platform section, an auxiliary central platform section hinged to said ledge to swing upwardly, auxiliary side platform sections arranged on opposite sides of the auxiliary central platform section, an auxiliary central top section hinged 85 at the rear of the main central top section to swing downwardly, and auxiliary side top sections mounted on opposite sides of the auxiliary central top section, the auxiliary side top sections being hinged to the auxiliary central section to swing upwardly thereon in order to fold in parallel relation with said auxiliary central section.
9. A portable band stand comprising a 90 rigid platform section, a rigid top section, sections hinged to the platform section to swing upwardly, sections hinged to the rigid top sections to swing downwardly, and braces detachably connecting the hinged top sections with the hinged platform sections, said braces having right and left handed threads at opposite ends thereof and the hinged top and platform sections having 95 pockets in which said threads engage.
10. A vehicle body having a main central platform section, main side sections hinged at opposite sides of the central platform section, an auxiliary central platform section hinged to the vehicle, adapted to 100 lie in a plane below the plane of the main central section, and auxiliary side sections movably mounted on opposite sides of the auxiliary central section in a plane with 105 the latter.
11. A portable band stand comprising a vehicle body having a rigid main platform section, main side sections hinged at opposite sides of the main platform section, a ledge arranged in rear of the main platform section in a plane below the latter, an auxiliary central platform section hinged to the ledge to lie in a plane therewith and 110 to swing upwardly, and auxiliary side sections movably supported on opposite sides of the auxiliary central platform section.

THEODORE DOSSENBACH.
